United States Patent Office

Des. 232,191
Patented July 23, 1974

232,191

RIGHT ANGLE DRIVE

John G. Fenic, Donald L. Kime, and William C. Raridan,
Dayton, and Read C. Viemeister, Yellow Springs, Ohio,
assignors to Chemineer, Inc., Dayton, Ohio

Filed Dec. 18, 1972, Ser. No. 316,069

Term of patent 14 years

Int. Cl. D15—05

U.S. Cl. D55—1 D

FIG-1

FIG-2

FIG-3

FIG-4

FIG-5

FIG. 1 is a perspective view of a right angle drive, with a motor shown in broken lines for illustrative purposes only;

FIG. 2 is a side view thereof;

FIG. 3 is a top view thereof;

FIG. 4 is a front view thereof; and

FIG. 5 is a rear view thereof.

We claim:

The ornamental design for a right angle drive, substantially as shown and described.
